RACING DICE GAME

Herman E. Stange, San Francisco, Calif.

Application November 2, 1953, Serial No. 389,515

3 Claims. (Cl. 273—146)

This invention relates to a game in which dice have been devised to enable the thrower or player to determine winner, second place, third place, etc., from colors and identifying indicia that simulate racing colors and members, and one of the objects of the invention is the provision of such dice whereby a player in one or several throws is enabled to determine said winner, second place, etc., without duplication.

For example, assuming there are eight entries, each having a different color and numbered "1" to "8" or any other desired indicia or symbols, so long as they are different, one of the dice will have eight faces and each face will have a color different from the others and a number, symbol or name, different from the others. When this die is rolled the uppermost face will indicate the winner and its color, from this color. Obviously the same die cannot be used to determine the second or third places since they might well return the same number on each throw as the winner. The present invention obviates the above possibility and enables the player to determine in one or several throws, as desired, the first, second and third places.

Other objects and advantages will appear in the description and in the drawings.

In the drawings

Fig. 1 shows a single eight sided die in positions showing all sides.

Fig. 2 is an end view of the dice of the set from which second place is determined.

Fig. 3 is a reduced size side elevational view of one of the dice of Fig. 2, as seen at right angles to the dice of Fig. 2.

Fig. 4 is an elevational view of one side only of the dice of the set from which third place or show is determined.

Fig. 5 is a reduced size view of one side of a set of three dice from which the odds for winner, second place and show are determined.

In detail, the die shown in different positions in Fig. 1 has eight equal sides, hence any one of the eight sides may be uppermost when the die is thrown. In other words, the die is balanced so that it cannot be controlled any more than the conventional properly balanced six sided dice. Any number of sides can be provided if this condition is observed.

Each of the sides of die has a different color and a different identifying indicia or symbol. In this case such indicia are numbers, since numbers are employed in conventional racing, as are colors. As indicated in Fig. 1, the side 1 may be green and bear the numeral "1," side 2 may be purple and bear the numeral "2." Side 3 is gold and bears the numeral "3," side 4 is brown and bears the numeral "4," side 5 is orange and bears the numeral "5," side 6 is blue and bears the numeral "6," side 7 is red and bears the numeral "7," and side 8 is silver and bears the numeral "8." Thus the numerals not only identify the sides but the colors as well and

2

after slight familiarity with the game the color green and No. 1 become synonymous.

A cast of this single die described above, and which die may be generally designated 9, will determine the 5 winner, which, for example, may be No. 1 and green.

The dice of Fig. 2 are eight in number, and each of these dice is provided with seven equal sides, or one side less than the number of sides on die 9. In order to produce a seven sided die that is balanced for rolling, 10 each die in Fig. 2 actually has fourteen sides equally spaced about a central axis 10 with said sides extending slantingly oppositely toward said axis from a central plane 11 bisecting each die perpendicular to said axis. Two corresponding sides such as 12, 13 (Fig. 3) extending from opposite sides of said plane actually constitutes 15 one of the seven sides of said die as there are seven pairs of such sides.

Inasmuch as the maximum diameter of each die in the aforesaid plane is substantially equal to the length 20 of each die along said axis, when each die is rolled, it will rest on one of the sides of one of said seven pairs of sides and the portion of the die that is uppermost will be the juncture between adjacent corresponding pairs of such sides.

25 The opposite ends of the dice in Fig. 2 are colored, the opposite ends of each die being the same color as one of the sides of die 9. Thus the dice of Fig. 2 will be numbered 21, 22, 23, 24, 25, 26, 27, 28. The die 21 has green ends, the same as side "1" of die 9. Die 26 has blue ends, the same as side "6" of die 9, etc. to die 28 which has silver ends the same as side "8" of die 9.

Between the colored ends of each of the dice 21 to 28, each die has seven differently colored equal areas that 30 extend over half of the sides of each corresponding pair 35 so that when each die is supported on a table on one of its seven flat sides, one of said colored areas will be uppermost. The colors of these seven areas are the same as the seven sides of the die 9, minus the color of the side that corresponds in color to the ends of the die of Fig. 2, and these areas are numbered to correspond to the numbers of the colors used.

For example, referring to die 21 which has green ends, this die will have its colored areas 30 to correspond in color and in the numbers identifying them, to the colors 45 on seven of the sides of die 9, but will not have a color area 30 in green or bearing the number "1."

From the foregoing, it will be apparent that if the cast of die 9 should result in the green side "1" being uppermost to indicate "1" as the winner, then a cast of the 50 die 21 having green ends, could return any number except "1" and any color except green, hence this would be the die that would be used to indicate second place.

Obviously die 9 and the dice 21 to 28 inclusive may be thrown or cast at one time, in which case the player 55 merely reads the top side of die 9 for first place winner and the top side of the die in the set 21 to 28 that has its ends of the same color as the top side of die 9 in order to determine the second place winner.

Where third place or show is to be determined, twenty-eight dice, as seen in Fig. 4 are required.

Each of the dice in Fig. 4 is six sided, or one side less than each of the dice of Fig. 2, and two sides less than the die of Fig. 1.

The dice of Fig. 4 may be generally designated 32, 60 and each of these dice bears two of the colors used for the sides of die 9 of Fig. 1 in different combinations of the pairs from the series of eight colors.

In the dice 32 the numbers that are omitted on each die are the numbers that correspond to the colors on the die. The other six numbers are on each die.

For example, the die 33 having green and orange in areas 34, 35 will have the numerals 2, 3, 4, 6, 7, 8

on its sides but not numerals "1" (green) and "5" (orange). Thus assuming that the cast of die 9 showed green to be the winner, and the cast of die 21 showed orange to be the second place winner, then the operator would throw die 33 to determine the third or show winner since a cast of die 33 could return any number except "1" and "5" which have already placed first and second. Or the operator could cast all 28 of the dice 32 and dice 21 to 28 and die 9 at the same time, and then merely pick out the first, second and third place winners.

If desired, several extra dice, which may be eight sided, can also be cast separately or at the same time to determine the odds for winner, second place and third place or show, these dice being differently colored so that one would be used for first, one for second and one for third inasmuch as the odds for the different places would vary from relatively high odds to relatively low odds according to the changes. Such dice are indicated at 40 in Fig. 5.

Generally speaking, it is seen that the present invention comprises movable devices each formed with a plurality of separately identified surfaces and identifying means on each of such surfaces distinguishing them from each other, and one of such devices for determining the winner has one more surface than the others. The number of other devices for second place is equal to the number of surfaces on the single device used to determine the winner. The identifying means on the surfaces of the second place devices corresponds to those on the surface of the single winning device except that a different one of each of the identifying means that is on said single device is omitted from each of the other (second place) devices and it is necessary for each of the second place devices to have a common means such as color, identifying each of the second place devices with each of the surfaces on the single winning device.

This principle could be carried to third and fourth place, etc., along the lines described for dice 32, but for practical purposes it would not usually go beyond third place; and where third places devices are used these have means common to both the first and second place device such as color, and each eliminates the two symbols or identifying means thereon that is represented by said two colors.

I claim:

1. A game comprising a plurality of separate, independently movable devices each formed with a plurality of separately identified surfaces and each movable to a position of rest in which any one of said surfaces will be in one common reading position only, for reading identifying means on said one of said surfaces, according to which surface is in said reading position when each device comes to said position of rest, different identifying means on the surfaces on each of said devices distinguishing each of such surfaces from the others, one of said devices having one of said separately identified surfaces more than the said separately identified surfaces on the other devices, the number of said other devices being equal to the number of said surfaces on said one

device and the identifying means on the said separately identified surfaces of each of said other devices corresponding to those on the said separately identified surfaces of said one device except that a different one of each 5 of the identifying means on said one device is eliminated from each of said other devices, and a common means identifying each of said other devices with each of the said separately identified surfaces on said one device, the identifying means eliminated from each of said other devices being the one on the surface on said one device 10 that has the same common means as the device from which said identifying means is eliminated.

2. A game comprising a plurality of separate, independently movable devices each formed with a plurality 15 of separately identified surfaces and each movable to a position of rest in which any one of said surfaces will be in one common reading position only, for reading identifying means on said one of said surfaces, according to which surface is in said reading position when each 20 device comes to said position of rest, different identifying means on the surfaces on each of said devices distinguishing each of such surfaces from the others, one of said devices having one of said separately identified surfaces more than the said separately identified surfaces 25 on the other devices, the number of said other devices being equal to the number of said surfaces on said one device and the identifying means on the said separately identified surfaces of each of said other devices corresponding to those on the said separately identified surfaces 30 of said one device except that a different one of each of the identifying means on said one device is eliminated from each of said other devices, and a common means identifying each of said other devices with each of the said separately identified surfaces on said one device, the identifying 35 means eliminated from each of said other devices being the one on the surface on said one device that has the same common means as the device from which said identifying means is eliminated, said identifying means being symbols and said common identifying 40 means being colors.

3. A game of the character described comprising a single die providing a plurality of faces, different indicia on said faces distinguishing each from the others, a color identified with each indicia also distinguishing each face 45 from the others, a first set of dice equal in number to the number of faces on said die, each die of said set having one less face than the number of faces on said single die and each die of said set bearing a color corresponding to that on one of the sides of said single die, 50 each of the faces on each die of said set having one of the said indicia on each of the faces of said single die less the indicia on the side of said single die that has the same color as that of the die of said set.
